(57) **CLAIM**

The ornamental design for a solar canopy system, as shown and described.

DESCRIPTION

FIG. 1 is a right side elevational view of a solar canopy system in accordance with our new design;

FIG. 2 is a rear elevational view thereof;

FIG. 3 is a front elevational view thereof;

FIG. 4 is a top plan view thereof; and,

FIG. 5 is a front perspective view thereof.

The broken lines in the figures are for the purpose of showing environmental structure and form no part of the claimed design.

The left side elevational view of the solar canopy system is not shown in the drawings or described in the specification and, therefore, forms not part of the claimed design.
